United States Patent Office

Des. 229,792

Patented Jan. 1, 1974

229,792

WALLET

Matt J. Vitel, Woodstock, Va. 22664

Filed Oct. 7, 1971, Ser. No. 187,599

Term of patent 14 years

Int. Cl. D3—02

U.S. Cl. D87—3 R

Fig. 1. Fig. 2. Fig. 3. Fig. 4.

FIG. 1 is a front elevational view of a wallet showing my new design;

FIG. 2 is a rear elevational view thereof;

FIG. 3 is a front elevational view with the loop strap secured at the uppermost snap;

FIG. 4 is a rear elevational view thereof;

FIG. 5 is a front elevational view with the loop strap secured at the intermediate snap;

FIG. 6 is a rear elevational view thereof;

FIG. 7 is a front elevational view with the loop strap secured at the lowermost snap;

FIG. 8 is a rear elevational view thereof;

FIG. 9 is a side elevational view taken from the right of FIG. 8; and

FIG. 10 is a top plan view thereof with the wallet in an open position.

I claim:

The ornamental design for a wallet, as shown.
